ESCUCHÉON PLATE FOR AN ELECTRIC POWER PANEL

Giorgio I. Spadaro, Northfield, Ill., assignor to Acme-Lite Manufacturing Co., Chicago, Ill., a corporation of Illinois

Filed Apr. 25, 1960, Ser. No. 60,316

Term of patent 14 years

(Cl. D26—13)

Fig. 1 is a perspective view of an escutcheon plate for an electric power panel, showing my new design;

Fig. 2 is a top plan view; and

Fig. 3 is a front elevational view thereof.

I claim:

The ornamental design for an escutcheon plate for an electric power panel, substantially as shown.
